UNITED STATES PATENT OFFICE.

WILSON H. ALEXANDER, OF PHILADELPHIA, PENNSYLVANIA.

SHIPPING-JACKET.

1,268,201.

Specification of Letters Patent. Patented June 4, 1918.

Application filed October 14, 1914. Serial No. 866,561.

To all whom it may concern:

Be it known that I, WILSON H. ALEXANDER, a citizen of the United States, and resident of Philadelphia, in the county of Philadelphia and State of Pennsylvania, have invented certain new and useful Improvements in Shipping-Jackets, of which the following is a description.

The invention relates to improvements in shipping jackets for cans, such as are employed to protect the contained vessels from rough handling and which act as non-conductive coverings to keep cool the contents of the vessels. It has for its object the provision of a flexible jacket that can be readily wrapped about a vessel and form a comparatively tight closure, and one that can be employed to hold ice upon the top of the vessel for refrigerating purposes.

The invention consists of a device of the novel construction hereinafter described, pointed out in the appended claims and illustrated by the accompanying drawings.

In the drawings, in which similar reference characters designate corresponding parts,

Figure 1 is a vertical sectional view, on the line 1—1 of Fig. 2, of a jacket embodying the invention, the jacket being shown in position on an ordinary milk-can.

Fig. 2 is a horizontal sectional view on the line 2—2 of Fig. 1.

Fig. 3 is a detail view showing the fastening device for one of the holding straps.

Fig. 4 is a perspective view, showing the inner side of a portion of the jacket.

Fig. 5 is a horizontal sectional view on the line 5—5 of Fig. 1.

The main part of the jacket consists of a flexible casing 1 of suitable waterproof material, such as a woven fabric embedded in plastic composition. The dimensions of this casing are such that it can be wrapped about the vessel with considerable overlap at its edges, as at 2, and so as to extend above the top of the can to form the chamber 3 above the same. By reason of the considerable overlap at 2 there will be a considerable area of contact between the surfaces of the edges and thereby form a comparatively tight joint. In the chamber 3 ice may be placed for refrigerating purposes. On the inner face of the casing are the vertical battens 4, secured thereto in any suitable manner, to bear against the outer wall of the vessel contained in the jacket. These battens not only

serve to strengthen the casing, but are spaced apart to form vertical air-spaces between the vessel and the casing. These air-spaces not only form non-conductors to the higher temperature outside of the jacket, but also form vertical passages leading down from the ice-chamber 3 alongside of the vessel into which flows the cold air from the ice-chamber and the cold water from the melted ice to cool the contents of the vessel inclosed by the jacket. The casing is held in place around the vessel by the straps 5 having the usual buckles 6.

In the inner edges of the battens 4 are the notches 7 to engage the rim of the vessel. Ordinarily the engagement of the rim of the vessel with these notches will hold the jacket from slipping off the vessel. As a further precaution against slipping, hooks 8 are secured to the lower ends of several of the battens to engage the bottom flange of the vessel.

To the inner face of the casing 1, between the lower ends of the battens 4, are the blocks 9 of elastic material. These blocks and the battens are so shaped that when the jacket is wrapped about a vessel the blocks will close the lower ends of the air-spaces or passages between the battens to prevent the escape of the cold air and drip from the bottom of the jacket.

A circular lid 10 fits in the upper end of the casing when the latter is wrapped about a cylindrical vessel to close the ice-chamber. On the under side of this lid is the plate 11 having tongues 12 projecting at intervals from its periphery. Each of these tongues will enter the space between two adjacent battens, and when the lid is turned it will engage the recess 13 in the side of one of the battens. With these tongues 12 in engagement with the recesses 13 the lid will be firmly held in place on the jacket. To prevent the accidental turning of the lid and the freeing of the tongues, a pin 14 is pushed through an opening in the lid back of one of the battens. By removing the pin the lid can be easily turned to free the tongues 12 from the recesses 13 so that the lid can be removed. The lid not only forms a cover for the ice-chamber, but it also acts to strengthen the upper end of the jacket when the latter is in place.

The jacket is particularly adapted to the protection of cans used in the shipment of milk. Before the milk is poured into the

can it is thoroughly chilled. After the can has been filled the jacket is wrapped about it and secured in place. The jacket not only protects the can against injury from rough handling, but through insulation serves to preserve the milk in its chilled condition. During cool weather the insulation provided by the jacket would be sufficient to preserve the milk in its chilled condition during shipment, but in hot weather ice could be placed in the chamber above the can. After each shipment the jacket should be removed and the can cleaned for the next shipment. Owing to its flexibility and means of securing the jacket can be easily removed from the vessel. Owing to the wide overlap of the meeting edges of the jacket the latter can accommodate cans of different diameters; also the notches at different elevations in the battens permit the jacket to be used with cans of different heights. When a jacket is removed from a can it can be spread flat to facilitate the cleaning and drying of the same, and a number of flattened jackets can be piled on one another to economize room. Also a removed jacket can be rolled into a small compact bundle for easy transportation separate from the can.

Having thus described my invention, what I claim and desire to secure by Letters Patent is:

1. In a shipping jacket, a removable flexible casing of heavy sheet fabric or like material shaped so that it can be wrapped around cans of different dimensions to form a temporary covering for the contained ves-

sel, vertical battens secured to the inner face of the flexible casing to bear against the wall of the contained vessel, said battens being spaced apart to form air-spaces between the 40 casing and the wall of the contained vessel, and fastening means for temporarily securing the casing around the contained vessel.

2. In a shipping jacket, a flexible casing to be wrapped around the vessel and to extend 45 above the top of the contained vessel to form a chamber thereover, vertical battens secured to the inner face of the casing to bear against the wall of the contained vessel, said battens being spaced apart to form air-spaces between the casing and the wall of the contained vessel with said air-spaces 50 communicating with the chamber formed above the contained vessel, and a lid to close the upper end of the chamber over the contained vessel.

3. In a shipping jacket, a flexible casing to be wrapped around the vessel, vertical 60 battens secured to the inner face of the casing to bear against the wall of the contained vessel, said battens being spaced apart to form air-spaces between the casing and the wall of the contained vessel, and blocks secured to the inner face of the casing between the lower ends of the battens to close the 65 air-spaces.

In testimony whereof I hereunto affix my signature in the presence of two witnesses.

WILSON H. ALEXANDER.
